UNITED STATES PATENT OFFICE

RAYMOND C. LEYDECKER, OF OMAHA, NEBRASKA

DESIGN FOR AN EMBLEM OR SIMILAR ARTICLE

Application filed February 27, 1930. Serial No. 34,875. Term of patent 3½ years.

To all whom it may concern:

Be it known that I, RAYMOND C. LEYDECKER, a citizen of the United States, residing at Omaha, in the county of Douglas and State of Nebraska, have invented a new, original, and ornamental Design for an Emblem or Similar Article, of which the following is a specification, reference being had to the accompanying drawing, forming part thereof.

Fig. 1 is a front view of an emblem or similar article showing my design, and Fig. 2 is an edge view.

I claim:

The ornamental design for an emblem or similar article, as shown.

RAYMOND C. LEYDECKER.
